ABSTRACT OF THE DISCLOSURE

This disclosure relates to prestressed rolling mills of the type in which the pass opening between the working rolls of the mill is set by spacing means which are displaceable relative to the bearing chocks of one roll of the mill and rest with their ends on the bearing chocks of another roll. The spacing means may operate either on the bearing chocks of the working rolls of the mill or on the bearing chocks of any back-up rolls for the working rolls.

The spacing means generally consist of screw spindles which are rotated for their axial displacement in nuts associated with the bearing chocks of the first roll.

The prestressing means are usually formed by hydraulic cylinder-and-piston units arranged between the bearing chocks of one of the two aforementioned rolls and the mill housings.

In known rolling mills of the above-described type, the screw spindles acting as spacing means were threaded into the bearing chocks of the first-mentioned roll. With this design, these bearing chocks had to be made extra large to accommodate the spindles, there being always at least two spindles for each chock, for reasons of symmetry. This increased the weight and bulk of the bearing chocks, particularly in the case where the spacing means operated on the bearing chocks of the back-up rolls of the mill. Moreover, the machining of the threads in the bearing chocks added to their cost.

Furthermore, it is general practice for the bearing chocks to remain on the rolls when the latter are taken out of the mill, in order to shorten the time required for the exchange of rolls. This makes it necessary to provide bearing chocks for each set of rolls. It is therefore desirable to reduce the bulk and cost of these bearing chocks.

It is one of the objects of the present invention to provide a prestressed rolling mill of the above-described type in which the drawbacks of the known arrangement of spacing means are overcome.

In prestressed rolling mills of the above-described type, means are sometimes provided for automatically controlling the opening of the gap between the working rolls so as to eliminate or compensate for any changes in that opening which might otherwise occur as a consequence of random changes in the roll-separating force. These means may include load cells for measuring the load in the spacing means, and further load cells for measuring the prestressing force. A control system having both types of load cells is described in our (accepted) British Pat. No. 1,100,581. Heretofore, it was not possible to provide in such a control system means for measuring the roll-separating force. This led to certain complications in the control means and in their operation.

It is another object of the present invention to provide

2

a prestressed rolling mill of the above-described type having automatic control means for the opening of the gap between the working rolls, which means include instrumentation for the direct measurement of the roll-separating force.

5 The invention is particularly adapted to be incorporated into prestressed rolling mills of the type having housings in whose windows the bearing chocks of the mills are accommodated.

10 According to the present invention, a prestressed rolling mill comprises housings, bearing chocks in windows of the housings, hydraulic prestressing means arranged between the housings and the bearing chocks of one mill roll, and spacing means displaceable relative to the bearing chocks of one roll of the mill and resting with their ends on the bearing chocks of another roll, said spacing means being in the form of screw spindles threaded into parts of the rolling mill external of the bearing chocks of both said rolls.

15 20 With this arrangement, there is no need to increase the bulk and weight of any of the bearing chocks, nor is it necessary to provide each set of bearing chocks with its own spacing means.

The parts into which the screw spindles acting as spacing means are threaded may be in the form of U- or saddle-shaped supports inserted into the windows of the rolling mill housings. The spindles are then threaded into nuts arranged in the leg or side portions of these supports, while the bearing chocks of one roll are received between 25 30 the side or leg portions, the ends of the spindles resting on the bearing chocks of the other mill roll.

Alternatively, the screw spindles acting as spacing means may be threaded into nuts formed in the mill housings themselves, in which case the housings have an 35 enlarged part through which the screw spindles pass, the bearing chocks of one roll being received between the enlarged parts, while the spindles rest with their ends on the bearing chocks of the other mill roll which is received between the non-enlarged parts of the housings.

40 45 Load cells may be provided in either form of the invention between the ends of the spacing means and the bearing chocks on which the spacing means rest, the load cells being adapted to measure the load in the spacing means. Further load cells may be arranged between the prestressing means and the rolling mill housings or the bearing chocks of the adjacent roll, whereby the prestressing force may be measured. It is then possible to control the prestressing force in the manner described in our British Pat. No. 1,100,581, whereby the opening of the roll-gap between the working rolls can be automatically controlled, and any changes in that opening which might otherwise occur as a consequence of random changes in the roll-separating force be eliminated or compensated.

50 55 With the mill according to the invention it is possible to replace either of the sets of load cells by load cells arranged between the parts into which the screw spindles acting as spacing means are threaded, and the bearing chocks received in these parts. These latter load cells will measure the roll-separating force. By measuring this force and the spacing load or the prestressing force, it is possible to control the prestressing force in such a manner that the same results are obtained as in the case of the control system according to our British Pat. No. 1,100,581, having regard to the fact that at all times in a mill 60 65 of the type described, the prestressing force is equal to the sum of the spacing load and the roll-separating force.

Two embodiments of the invention will now be described by way of example with reference to FIGS. 1 and

2 and of the accompanying drawings, in which lateral views, partly in section of horizontal prestressed rolling mills in which the invention is incorporated are illustrated.

The rolling mills according to FIGS. 1 and 2 are both of the four-high type. Each mill comprises on each side thereof a housing 2 with a window 4 for receiving therein upper and lower bearing chocks 6 and 8 for upper and lower backing rolls 10 and 12 respectively. Bearing chocks 14 and 16 for upper and lower work rolls 18 and 20 respectively are nested in the chocks of the associated backing rolls. Hydraulic balancing units 22 are arranged between the back-up chocks 6 and 8, and hydraulic balancing units 24 are arranged between the work roll chocks 14 and 16. Hydraulic prestressing units 26, each comprising a cylinder 28 and a ram 30, are arranged between the lower transverse parts 32 of the housings 2 and the underside of the lower back-up chocks 8.

According to FIG. 1, upper back-up chocks 6 are received in U- or saddle-shaped supports 34 whose downwardly depending side or leg portions 36 embrace the chocks 6 at both their sides, while the bridge portion 38 of the supports 34 extend across the upper side of the chocks 6 and along the insides of the upper transverse parts 40 of the housings 2. In the embodiment shown in FIG. 1, the supports 34 fit closely into the windows 4, and their side or leg portions 36 contact the sides of the chocks 6. The top of these chocks is slightly spaced-apart from the bridge portion 38 for a purpose to be specified later.

Spacing means for setting the pass opening between the working rolls 18 and 20 are provided in the form of vertical spindles 42 which freely extend through the transverse top part 40 and most of the leg portions 36 of the support 34 and are screw-threaded at their ends into nuts 44. The latter are secured to the leg portions 36 so that rotation of the spindles 42 moves those spindles axially relative to the chocks 6.

The spindles 42 rest with their lower ends on the lower back-up chocks 8, the latter being made of greater width than the upper back-up chocks 6 for that purpose. The spindles are preferably arranged in pairs on each back-up chock 6, the two spindles of a pair being disposed at opposite sides of the common axial plane of the mill rolls and symmetrically with respect to that plane. Pressure pads 46 are arranged below the lower ends of the spindles 42. The latter are driven at their upper ends through splined connections with bevel gears 48 and a common shaft 50, so that the spindles 42 rotate in unison. Further means, not shown, may be provided to ensure synchronism between the rotation of the spindles 42 of one back-up chock 6 with those of the spindles of the other back-up chock. The shaft 50 is driven by an electric motor, not shown.

When it is desired to adjust the pass opening between the working rolls 18 and 20, the spindles 42 are simultaneously rotated through the afore-described drive, whereby they are raised or lowered relative to the upper back-up chocks 6 in accordance with the direction of the rotation of the spindles. The lower back-up chock 8 with the lower back-up roll 12, as well as the lower work roll chock 16 with the lower work roll 20, follow the movements of the spindles 42 as the chocks 8 are kept in contact with the lower ends of the spindles 42 at all times by means of the hydraulic units 26. If desired, the pressure in these units may be lowered during the adjustment of the spindles 42.

In the embodiment of FIG. 2, corresponding parts have been denoted by the same reference numbers as in FIG. 1. In the case of FIG. 2, the spindles 42 are arranged in the housings 2, the latter having to this end internal enlargements through which the spindles pass. There is then no necessity for providing separate supports 34. Otherwise, the arrangements of the parts of the rolling mill shown in FIG. 2 is similar to that of FIG. 1.

In both cases, spindles 42 are arranged in parts external of any bearing chocks of the rolling mill. It is therefore possible to exchange the rolls, together with their bearing

chocks, without having to manipulate the spindles. Furthermore, the upper back-up chocks 6 can be made lighter and more cheaply. Saving weight is important because this back-up chock has to be lifted out of the mill each time the working rolls 18 and 20 are exchanged, while the lower back-up chocks 8 may remain in place.

It is understood that both sides of the rolling mill are identical and that each housing 2 thereof has either separate supports 34 for the upper back-up chocks 6 (FIG. 1) or that each housing 2 has enlarged parts (FIG. 2).

If desired, automatic control means may be provided in either of the rolling mills of FIG. 1 or FIG. 2 for ensuring that the pass opening between the working rolls 18, 20 is not changed by any of the random changes of the roll-separating force which occur during a rolling operation, thereby ensuring a rolled product of uniform thickness from end to end. Load cells 52 are then provided between the pressure pads 46 and the lower back-up chocks 8. These load cells are preferably of a type in which the measurements are transformed into electric signals and in which there is a linear relationship between the loads registered and the signals emitted. The load cells 52 indicate the load S—the so-called "spacing load"—in the spindles 42, this load being at all times the difference between the prestressing force P and the roll-separating force R. By providing the control system described in our British Pat. No. 955,164, it is possible to eliminate those changes in the pass-opening between the work rolls 18, 20 caused by changes in the roll-separating force R and attributable to the chock spring of the mill.

When it is desired to take into account changes attributable both to chock spring and to roll spring, load cells, not shown here, may be positioned between the prestressing units 30 and the lower back-up chocks 8, whereby the prestressing force P is measured. Control of the prestressing force can then be effected by the system described in our British Pat. No. 1,100,581.

Alternatively, load cells 54 may be placed between the upper back-up chocks 6 and the bridge parts 38 of the supports 34 (FIG. 1) or between the back-up chocks 6 and the upper transverse parts 40 of the mill housings (FIG. 2). These load cells measure the roll-separating force R. It is then possible to dispense either with the load cells not shown here and arranged next to the prestressing units 30, or with the load cells 52 which measure the spacing load. In the first case, control of the prestressing force is effected by the measurement of the roll-separating force R and the spacing load S; in the second case, by the measurement of the roll-separating force R and the prestressing force P. As the prestressing force P is at all times equal to the sum of the spacing load S and the roll-separating force R, the control methods applicable in the case of measurements of S and R or P and R may be readily obtained by substitution of $R=P-S$ in the equations given in our British Pat. No. 1,100,581.

We claim:

1. A prestressed rolling mill comprising housings, rolls arranged at opposite sides of the gap through which the rolled articles pass, bearing chocks for supporting said rolls in said housings and adjustable roll-spacing means comprising threaded spindles, arranged on both sides of the common axial plane of said rolls, said spindles being mounted in the housings and extending alongside and outwardly of the bearing chocks of a first roll at one side of said gap and resting with their ends on the bearing chocks of a second roll at the opposite side of said gap, the mating threads for said spindles being provided on parts of the mill externally of the bearing chocks of both said rolls and embracing the bearing chocks of said first roll.

2. A prestressed rolling mill according to claim 1 in which the parts of the housing provided with the threads for said spindles are U-shaped, the legs of said U-shaped parts being provided with said threads and straddling

the bearing chocks of said first roll and the bridge portion of said U-shaped parts being inserted between said bearing chocks and said housings.

3. A prestressed rolling mill according to claim 1 in which load cells are provided between the ends of said spindles and the bearing chocks of said second roll.

4. A prestressing mill according to claim 2, in which the bearing chocks of said first roll are narrower than the bearing chocks of said second roll so that the bearing chocks of said second roll have shoulders projecting beyond the width of the bearing chocks of said first roll, and in which the spindle portions rest with their ends on said shoulders and pass outside and alongside the bearing chocks of said first roll.
